UNITED STATES PATENT OFFICE.

HENRY W. PITZ, OF PHILADELPHIA, PENNSYLVANIA.

DESIGN FOR A CALENDAR.

SPECIFICATION forming part of Design No. 26,537, dated January 19, 1897.

Application filed November 21, 1896. Serial No. 613,029. Term of patent 14 years.

To all whom it may concern:

Be it known that I, HENRY W. PITZ, a citizen of the United States, residing in the city and county of Philadelphia, State of Pennsylvania, have invented and produced a new and original Design for a Calendar, of which the following is a specification, reference being had to the accompanying drawings, forming part thereof.

10 The leading feature of my design for a calendar is a field with a rim and an open frame set out from said field.

Figure 1 represents a perspective view of a calendar embodying my design. Fig. 2 represents a section thereof on line $x\ x$, Fig. 1.

15 In the drawings, A designates a field, and B the rim thereof.

C designates an open frame which joins the three walls D E F, which are raised from said field, thus setting out said frame.

20 Between the upper end of the frame and the adjacent portion of the field back of said end is the passage G.

The tops of the sides H of the frame C are joined by the cross-bar J.

25 What I claim is—

The design for a calendar substantially as described and shown.

HENRY W. PITZ.
